UNITED STATES PATENT OFFICE

156,801

RIBBON HOLDER

Magdalene B. Zeglen, Minneapolis, Minn.

Application October 25, 1948, Serial No. 149,273

Term of patent 14 years

(Cl. D80—9)

To all whom it may concern:

Be it known that I, Magdalene B. Zeglen, a citizen of the United States, residing at Minneapolis, county of Hennepin, and State of Minnesota, have invented a new, original, and ornamental Design for Ribbon Holders, of which the following is a specification, reference being had to the accompanying drawing, forming part thereof.

I claim:

The ornamental design for a ribbon holder, substantially as shown.

MAGDALENE B. ZEGLEN.
